DESIGN FOR A COAT

Nathan A. Rauch, New York, N. Y.

Application January 21, 1941, Serial No. 98,255

Term of patent 3½ years

To all whom it may concern:

Be it known that I, Nathan A. Rauch, a citizen of the United States, residing in New York city, in the county of New York and State of New York, have invented a new, original, and ornamental Design for a Coat, of which the following is a specification, reference being had to the accompanying drawing, forming part thereof.

Fig. 1 is a front view of a coat showing my new design, and

Fig. 2 is a fragmentary side view thereof.

The back of my design is conventionally plain.

The characteristic feature of my design resides in the combination on the double collared coat disclosed of the specific self-material, self-colored trimming bands forming the yoke and pockets, as shown.

I claim:

The ornamental design for a coat, substantially as shown and described.

NATHAN A. RAUCH.
